United States Patent Office

Des. 186,449
Patented Oct. 27, 1959

186,449

GAME BOARD OR SIMILAR ARTICLE

Francis L. Phillips, Alexandria, Va.

Application April 21, 1959, Serial No. 55,604

Term of patent 14 years

(Cl. D34—5)

FIG. 1

I claim:

The ornamental design for a game board or similar article, as shown.
